UNITED STATES PATENT OFFICE

JAMES R. HIGHT, OF LONG BEACH, CALIFORNIA

SANITARY GARBAGE CAN

Application filed February 14, 1930. Serial No. 428,333.

An object of my invention is to provide a sanitary garbage can of sturdy construction, and which has no obstructions to hinder the removal of the garbage therefrom.

5 Another object is to provide a novel means of sealing the lid upon the can.

Still another object is to provide a novel sealing means between the lid and the can. This sealing means also acting to close the 10 opening in the outer annular trough when the lid is removed.

Other objects, advantages, and features of invention may appear from the accompanying drawing, the subjoined detailed description and the appended claims.

In the drawing

Figure 1 is a side elevation of my garbage can.

Figure 2 is an enlarged fragmentary, 20 transverse, sectional view of the upper part of the can.

Figure 3 is a side elevation of the spring actuated ring.

Figure 4 is a fragmentary sectional view 25 of the bottom of the can.

Referring more particularly to the drawing, the numeral 1 indicates a cylindrical body, the inner surface of which is straight from top to bottom so that there is no obstruction to the removal of the garbage from the can. The bottom of the can is convex as shown at 2, and a ring 3 is secured to the bottom of the can, preferably by welding or the like, and depends below the convex bottom 2 so that the can is supported thereon. This ring is preferably made of strap iron of substantial weight.

A plurality of holes 4 extend through the ring 3 so that the bottom of the can is well 40 ventilated and will therefore not rust so readily. An angle-iron ring 5 is secured to the body 1 adjacent the upper end thereof, and is welded or otherwise suitably secured to the body of the can. The angle-iron 5 forms a trough with the body 1, as shown at 6. The upper end of the body is flanged outwardly a slight amount as shown at 7. The purpose of which will be further described.

50 A lid 8 closes the top of the can and is

formed with an annular depending flange 9. The flange 9 enters the trough 6 and if desired, this trough may be filled with water or the like to exclude insects from the can. The water seal would also be particularly 55 advantageous where the can is kept in the house or in a doctor's office, or the like.

If desired, the following means may be employed to seal the lid, namely, a ring 10 fits closely in the trough 6 and a plurality of 60 springs 11 are secured to the ring and press against the angle-iron 5, thus normally urging the ring upwardly against the flange 9. Packing 12 is provided between the flange and the ring. This packing being of some 65 soft material such as felt or the like. When the lid is placed on the can, the ring 10 is depressed against the tension of the springs 11 and the felt packing 12 is pressed against the flange thus sealing the lid against the 70 escape of odors or the ingress of insects.

The small flange 7 at the top of the body 1 tends to limit the upward movement of the packing 12 and the ring 10. When the lid is removed, the ring pushes the packing upwardly into engagement with the flange 7 and thus presents a comparatively flush surface at the top of the body 1. Thus when any material is deposited in the can, it will not readily lodge in the trough 6 because of the position of the packing 12 adjacent the top of the trough. Also when the can is being emptied, the flange 7 prevents the ring 10 and the packing 12 from falling out of the 80 trough.

To press the lid tightly on to the top of the can, I provide a yoke 13 which is pivotally mounted on the top of the lid 8, and also acts as a handle. The bail 14 of the can when swung into the position shown in Figure 1, engages the top of the yoke 13 and thus presses the lid tightly in closed position. A slight depression 15 is formed in the top of the yoke into which the bail falls, thus preventing the accidental dislodgment 85 of the bail.

Having described my invention, I claim:

1. In a garbage can including a cylindrical body, an angle-iron ring secured to the body adjacent the top thereof, said ring forming 100

- a trough on the outside of the body, a lid, a flange depending from the lid and extending into the trough, means securing said lid in closed position, a ring in the trough, spring means urging the ring upwardly and packing on the ring, said packing pressing against said flange to seal the lid.
2. In a garbage can including a cylindrical body, an angle-iron ring secured to the body adjacent the top thereof, said ring forming a trough on the outside of the body, a lid, a flange depending from the lid and extending into the trough, a ring in the trough, spring means urging the last named ring upwardly, packing on the ring, said packing pressing against said flange to seal the lid, and a ring secured to the bottom of the body, said last named ring depending below the body and having a plurality of holes therethrough.
- 10 3. In a garbage can comprising a cylindrical body, an out-turned flange on the top of the body, an angle-iron ring secured to the body adjacent the top thereof and forming a trough with the body, a lid, a flange on 25 the lid extending into said trough, a yoke hingedly mounted on the lid, a bail on the body engaging said yoke to hold the lid in closed position, a ring in said trough, springs secured to the bottom of the ring and pressing against said angle-iron ring thereby urging the ring in the trough upwardly and packing on said ring in the trough, said packing pressing against the flange to seal the lid.
- 30 35 In testimony whereof, I affix my signature.
JAMES R. HIGHT.
